A. L. SOHM

RADIATOR ATTACHMENT

Filed Jan. 20, 1925

Inventor

ALFRED L. SOHM

Ch. Parker
Attorney

UNITED STATES PATENT OFFICE.

ALFRED L. SOHM, OF CHICAGO, ILLINOIS.

RADIATOR ATTACHMENT.

Application filed January 20, 1925. Serial No. 3,701.

To all whom it may concern:

Be it known that I, ALFRED L. SOHM, a citizen of the United States, residing at Chicago, in the county of Cook and State 5 of Illinois, have invented certain new and useful Improvements in Radiator Attachments, of which the following is a specification.

This invention relates to radiator attachments for motor vehicles and more particularly to a device for securing radiator ornaments, signal devices and the like to automobile radiators to prevent their unauthorized removal or accidental loss therefrom.

15 An important object of the invention is to provide a device of the above mentioned character which is adapted to be connected to filling spouts of varying sizes, whether provided with internal or external threads.

20 A further object of the invention is to provide such a device provided with a plurality of gripping means adapted to engage the filling spout of a radiator to prevent removal of the signal or the like, common means being employed for actuating the gripping members.

25 A still further object is to provide gripping means for securing the device in place on the radiator in such manner as to prevent loss of water or water vapor from the 30 radiator.

Other objects and advantages of the invention will be apparent during the course 35 of the following description.

35 In the drawings I have shown one embodiment of the invention. In this showing—

Figure 1 is a central vertical sectional view showing the device in place on a radiator, parts being shown in elevation,

40 Figure 2 is a horizontal sectional view through the device, and,

Figure 3 is a detail perspective view of the gripping members and operating means therefor.

45 Referring to the drawings the numeral 10 designates an attachment mounted adjacent the filling spout of an automobile radiator and shown in the present instance as a signal provided with a movable cap 11 adapted 50 to be actuated by fluid pressure created in the radiator under abnormal conditions to serve as a warning to the operator. The signal 10 is adapted to be mounted over the usual radiator 12 having a filling spout 13 which

is threaded as at 14 for connection with the 55 usual cap employed.

The present invention includes a base designated as a whole by the reference numeral 15 adapted to be arranged over the spout of the radiator. The base 15 may be suitably 60 hinged as at 16 to the signal 10 at one side and may be provided at its opposite side with locking means 17 of any desired type to maintain the signal in closed position as shown in Figure 1. The member 15 is provided in its upper face with an annular groove 18 in which is arranged a packing ring 19 preferably formed of rubber and adapted to be engaged by a flange 20 projecting from the bottom of the signal. The 65 engagement of the flange 20 with the packing 19 is adapted to form an air-tight joint between the signal and the base 15.

The base member 15 comprises a pair of spaced substantially annular walls 21 and 75 22 providing therebetween a circular space 23 of substantial width. It will be obvious that the space 23 is adapted to receive radiator spouts 13 of varying diameters threaded either externally or internally. A washer 80 or packing ring 24 is arranged in the upper end of the space 23 and is adapted to engage against the upper end of the filling spout as shown in Figure 1. A spring washer 85 25 is provided for maintaining a leak-proof 90 contact between the ring 24 and the filling spout to prevent loss of water or water vapor from the radiator. The inner wall 22 is provided at spaced points with thickened 95 portions or lugs 26 as shown in Figures 90 1 and 2 and these lugs are connected at their lower ends by a spider 27. The spider is provided with a central upstanding bearing 28 having a central aperture 29 adapted to 100 rotatably receive a vertical pin 30. The upper end of the pin 30 is provided with a plurality of preferably integral cams 31, one of which is provided in one face with ratchet teeth 32 as clearly shown in Figures 2 and 3. The pin 30 is provided above the cams 105 31 with an upward extension 33 provided with a screw-driver slot 34. The lower end of the pin 30 may be upset as at 35 to retain it in position and a washer 36 is arranged between the upset end of the pin and the 110 lower face of the bearing 28.

Each of the lugs 26 is provided with a radial opening 37 in which are slidably

mounted a plurality of gripping members 38 arranged substantially in the same plane as the cams 31 as will be obvious. Each of the gripping members 38 is provided at its outer end with a projecting point 39 for a purpose to be described. One of the gripping members is provided at its inner end with a reduced portion 40 terminating at its end in a beveled face 41 adapted to engage against the ratchet teeth 32 as shown in Figure 2.

As shown in Figures 1 and 2, the member 15 is provided at opposite sides with projecting preferably ornamental arms 42. It will be obvious that these arms facilitate the application of the device to the radiator and serve to present a pleasing ornamental appearance. It will be obvious that the device may be provided with any suitable ornamentation.

The operation of the device is as follows:

When it is desired to place the device in position on a radiator the locking device 17 is released and the signal swung backwardly about the hinge 16. The member 15 is then arranged over the filling spout and pressed downwardly as far as possible so that snug engagement is obtained between the packing ring 24 and the upper end of the filling spout. The end of the screw driver is then arranged in the slot 34 and the pin 30 is rotated in a clockwise direction as seen in Figure 2. Rotation of the pin is continued as far as possible and this rotation engages the cams against the inner ends of the pins 38 to project them outwardly until the pointed ends penetrate a slight distance into the metal of the spout as will be obvious. When the pin 30 has been revolved as far as possible the return thereof to original position is prevented by engagement of the ratchet teeth 32 against the inner reduced end 40. If the device has been properly applied so that the outer ends of the gripping members 38 are in firm engagement with the spout the device cannot be removed since counterclockwise rotation of the pin 30 is impossible.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. A device of the character described comprising a member having a portion adapted to be arranged adjacent the filling spout of an automobile radiator, clamping means carried by said portion and movable in one direction to engage the filling spout, and actuating means movable in one direction for moving said clamping means to

engaging position, said last named means having a portion adapted to engage said clamping means to positively prevent movement of said actuating means in the opposite direction.

2. A device of the character described comprising a member having a portion adapted to be arranged adjacent the filling spout of an automobile radiator and provided with an opening, a pin arranged in said opening and slideable in one direction to engage the filling spout, and actuating means carried by said member and movable in one direction for moving said pin to engaging position, said actuating means having a portion adapted to engage said pin to positively prevent movement of said actuating means in the opposite direction.

3. A device of the character described comprising a base having a portion adapted to be arranged within the filling spout of an automobile radiator and provided with an opening, a clamping pin slidably mounted in said opening and movable outwardly to engage the filling spout, and means rotatable in one direction for moving said clamping pin outwardly, said rotatable means having a portion adapted to engage said clamping pin to positively prevent reverse rotation of said rotatable means.

4. A device of the character described comprising a base having a depending cylindrical portion adapted to be arranged within the filling spout of an automobile radiator and provided with a plurality of radial openings, clamping pins slidably arranged in said openings, and a cam member rotatably mounted in said cylindrical portion and adapted upon rotation in one direction to move said clamping pins outwardly into engagement with the filling spout, said cam member being provided adjacent one of said pins with a ratchet tooth adapted to be engaged thereby to prevent reverse rotation of said cam member.

5. A device of the character described comprising a base having a pair of depending spaced cylindrical portions adapted to receive the filling spout of an automobile radiator therebetween, said cylindrical portions being concentrically arranged, the inner cylindrical portion being provided with a plurality of radial openings, clamping pins slidably arranged in said openings, a vertical bearing carried by said inner cylindrical portion axially thereof, a pin journaled in said bearing, and a cam member secured to said pin and adapted upon rotation in one direction to move said clamping pins outwardly into engagement with the filling spout, the portion of said cam member engaging one of said pins being provided with ratchet teeth adapted to engage against the inner end of said pin

to prevent reverse rotation of said cam member.

6. A device of the character described comprising a base having a depending portion adapted to be arranged within the filling spout of an automobile radiator and provided with a plurality of radial openings, pins slidably arranged in said openings and a member rotatably carried by said depending portion, said rotatable member being provided with a plurality of cam faces normally arranged between said pins and adapted to engage the latter upon rotation of said rotatable member, one of said pins being provided at its inner end with 15 a tooth, one of said cam faces being provided with a coacting tooth adapted to engage the tooth of said pin after said rotatable member has been rotated a sufficient distance to force the outer ends of said pins into 20 engagement with the filling spout.

In testimony whereof I affix my signature.

ALFRED L. SOHM.
